US00D836724S

(12) **United States Design Patent** (10) **Patent No.:** **US D836,724 S**
Kurscheidt (45) **Date of Patent:** **** Dec. 25, 2018**

- (54) **LABEL FOR LIQUIDS FOR PHARMACEUTICAL PURPOSES AND RADIOLABELING**
- (71) Applicant: **ITM Isotopen Technologien München AG**, Garching (DE)
- (72) Inventor: **Markus Kurscheidt**, München (DE)
- (73) Assignee: **ITM Isotopen Technologien München AG**, Garching (DE)
- (**) Term: **15 Years**
- (21) Appl. No.: **29/644,223**
- (22) Filed: **Apr. 16, 2018**
